CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL SWITCH.

1,414,413.

Specification of Letters Patent.

Patented May 2, 1922.

Application filed November 16, 1917. Serial No. 202,344.

To all whom it may concern:

Be it known that I, CHARLES H. HODGKINS, a subject of the King of Great Britain, and a resident of Pittsburgh, in the county of 5 Allegheny and State of Pennsylvania, have invented a new and useful Improvement in Electrical Switches, of which the following is a specification.

My invention relates to overload trip 10 switches and particularly to means for effecting the resetting of such switches.

One object of my invention is to provide an overload trip switch of the above-indicated character with electrically operated 15 means for resetting the switch when the same has been opened.

In overload trip switches which are now in service, means, such as latches, are provided for holding the same in an open position 20 until the latches are removed to permit the resetting of the switches. Thus, when overload trip switches, which are now in service on supply lines, are constantly subjected to overloads, it is essential to provide 25 means for quickly and conveniently resetting the switches when the same have been opened to break the power circuits. Moreover, it is desirable to provide remotely disposed means for effecting a resetting of the 30 switches.

In a system constructed in accordance with my invention, an electrically controlled means, that may be controlled at a distance from the switch is provided for releasing 35 the latch which maintains the trip switch in an open position.

In the accompanying drawing, Fig. 1 is a side elevational view, partly in section, of a switch constructed in accordance with my 40 invention; and Fig. 2 is a front elevational view of the switch illustrated in Fig. 1.

Referring to the drawing, a switch 1 is mounted upon a frame 2 that is secured to a support 3 in any suitable manner, as for 45 example, by bolts 4. The switch 1 embodies a coil 5 that is mounted within the supporting bracket 2, a core member 6 which operates within the coil 5 and is controlled thereby, a dash-pot 7 for governing the action 50 of the core member 6, and a switch member 8.

The switch member 8 is pivotally mounted upon the supporting bracket 2 and is provided with a contact member 9 for bridging 55 two contact terminals 10 and 11 that are mounted upon the support 3, when the switch

is in a closed position. The switch member 8 is also provided with a projecting portion 12 to be engaged by a latch 13, for a purpose to be set forth hereinafter. A spring 14 is provided for normally maintaining the 60 switch member 8 in a position to bridge the contact terminals 10 and 11.

An arm 15, which is pivotally connected, intermediate its ends, to the supporting bracket 2, has a latch 13 formed on one end 65 thereof and has an armature 16 connected to the other end thereof which is operated by means of a coil 17. A non-magnetic coil spring 18, which is mounted on the supporting bracket 2, is provided for maintaining 70 the arm 15 in a position to maintain the latch 13 in engagement with the portion 12 of the switch member 8.

Adjacent to the contact terminals 10 and 11, are provided two auxiliary contact terminals 19 and 20 which are bridged by a switch member 21 when the contact member 9 breaks contact with the contact terminals 10 and 11. The switch member 21 is pivotally mounted on the contact terminal 20 75 and is provided with an arm 22 which is operated by the switch member 8 to disconnect the contact member 21 from the contact terminal 19 whenever the switch member 9 bridges the contact terminals 10 and 11. A 80 plunger 23, which is mounted on the bracket 2, is operated by the core member 6 to release the switch member 8. A push button 24 is provided for completing a circuit through the coil 17 whenever the switch 1 is 85 in a released position and the contact terminals 19 and 20 are bridged by the contact member 21.

In case the trip switch is in the position illustrated in the drawing and the coil 5 is 90 subjected to an overload, the plunger 23 is moved by the core member 6 to give the switch member 8 a rotative movement in order to break contact between the contact terminals 10 and 11 and the contact member 9 and to permit the latch 13 to engage the projecting portion 12 so as to hold the switch 1 in an open position. Inasmuch as the switch member 8 is in an open position, the contact member 21 is moved by a spring 21^a to bridge 100 the contact terminals 19 and 20 and to prepare a circuit for the coil 17 which is completed by the push button 24.

In case it is desired to reset the switch 1, the push button 24, which may be disposed 110

at any distance from the operating part of the trip switch, is operated to complete a circuit from the battery 25 through the coil

17. Thus, the coil 17 is energized to attract 5 the armature 16 and to raise the latch 13 in a manner to permit the coil spring 14 to close the switch member 8.

Modifications in the apparatus and arrangement and location of parts may be 10 made within the spirit and scope of my invention, and such modifications are intended to be covered by the appended claims.

I claim as my invention:

1. A switch mechanism comprising a 15 pivoted contact-controlling member having a circuit closing and a circuit opening position, and a latch member yieldingly engaging the pivoted member in one position of the pivoted member and restraining said 20 member in its other position when said pivoted member is actuated thereto.

2. A switch mechanism comprising a plurality of stationary contact members, a bridging member therefor, a pivoted member 25 for supporting and controlling the pivoted member, means for causing the bridging member to yieldingly engage the stationary contact members and a latch member normally yieldingly engaging the pivoted member and adapted to restrain said 30 member in a predetermined biased position upon the disengagement of the stationary contact members by said pivoted member and the actuation thereof to the predetermined biased position.

3. A switch mechanism comprising a main switch, a pivoted member of L-shape having a contact member disposed at one end and a controlling spring at the other, a main winding 40 for actuating the pivoted member, a latching member of L-shape adapted to engage and to restrain the spring end of the pivoted member, a spring disposed at the other end of the latching member to control 45 the movement thereof, and an auxiliary winding disposed adjacent thereto having its axis perpendicular to that of the main winding and utilizing the supporting structure thereof for its magnetic circuit.

50 4. A switch mechanism comprising two windings disposed with their axes perpendicular to each other, pivoted members of substantially L-shape actuated by each winding, a spring member for controlling the actuation of the pivoted members, a contact member disposed on one of the pivoted members, the other pivoted member being adapted to engage and to latch the contact-bearing member when said member is actuated, 55 60 an auxiliary switch opened by the main

switch when said switch is closed and means for closing the auxiliary switch when the main switch is open.

5. A switch mechanism comprising two windings, two pivoted members of substantially L-shape respectively controlled thereby, one of the members supporting a contact member at one end and adapted to be engaged and latched at the other end by the second member when the former member is 65 actuated to the open position of the switch and a pivoted auxiliary contact member controlled at one end by the contact-bearing member and at the other end by a spring member, the main contact and the auxiliary 70 contact members being so disposed that one is disengaged when the other is engaged with its corresponding stationary contact member.

6. A switch mechanism comprising an operating coil, a switch, a pivoted supporting member therefor, a latch for maintaining the pivoted member in a biased position, a core member having relatively large inertia subject to the energization of the operating coil, a movable member disposed in 85 the path of the core member and adapted, upon the impact of the core member, to move the supporting member to a position at which it may be engaged and restrained by the latch. 90

7. A switch mechanism comprising a pivotally mounted switch member, a spring for normally maintaining the switch member in one position and a latch directly engaging the switch member for restraining the switch member in another position, and operating mechanism therefor comprising a coil, a pin member having relatively small inertia for actuating the switch member to its latch-controlled position and an independently movable core member having relatively large inertia and responsive to the coil to quickly actuate the pin member having the small inertia to actuate the switch member. 95

8. A switch comprising a contact member, a pivoted supporting member therefor, resilient means for biasing the pivoted member to one position, a movable member having relatively small inertia and movable in a direction to counter-balance the biasing effect of the resilient means, and a latch to engage and restrain the pivoted member in a second biased position upon the counter-balancing of the resilient means by the movable member. 100

In testimony whereof, I have hereunto subscribed my name this 24th day of Oct., 1917.

CHARLES H. HODGKINS.
